UNITED STATES PATENT OFFICE.

IVAN WIDE, OF CHICAGO, ILLINOIS, ASSIGNOR OF ONE-HALF TO CARL H. HALVORSEN, OF CHICAGO, ILLINOIS.

LOCK.

SPECIFICATION forming part of Letters Patent No. 722,194, dated March 3, 1903.

Application filed August 11, 1902. Serial No. 119,272. (No model.)

To all whom it may concern:

Be it known that I, IVAN WIDE, a citizen of the United States, residing at Chicago, in the county of Cook and State of Illinois, have invented certain new and useful Improvements in Locks, of which the following is a specification.

One of the objects of this invention is the production of a lock combining simplicity of construction with a high degree of efficiency.

A further object of the invention is to make a lock readily alterable when it is desirable to change the form of the key.

In the accompanying drawings, Figure 1 is a longitudinal sectional view of my improved lock, taken on dotted line 1 1 of Fig. 4. Fig. 2 is a sectional view taken on the same plane as the last preceding figure, but showing the parts in positions different therefrom. Fig. 3 is a transverse sectional view taken on dotted line 3 3 of Fig. 1, but with the key removed and the front plate supplied. Fig. 4 is a transverse sectional view taken on dotted line 4 4 of Fig. 1. Fig. 5 is a side elevation 25 of the guard-plate of this lock. Fig. 6 is a similar view of the tumbler-barrel.

In the construction of a lock embodying the features of my invention I provide a case 1, having the front plate 2, adapted to be secured to said case in any suitable manner. The case is provided with a suitable opening 3 near the lower part of its forward end for the reception of a slidable bolt 4, which bolt is thrown into and normally held in a locked 35 position by means of the spring 5, located between the rear end of said bolt and the rear end of the case 1 and mounted upon the stud 6, formed integral with the case 1. The bolt 4 is provided with a stop-shoulder 7 for limiting its forward movement and with an operating-shoulder 8.

The case 1 and its front plate 2 are provided with coincident openings 9 and 10 for receiving the lock-barrel 11, the trunnions 12 of 45 which are rotatably supported within said openings 9 and 10. The lock-barrel 11 is provided with a longitudinal key-slot 13, extending from end to end of said barrel and opening at one side thereof. Near one end said 50 barrel is provided with a stud 14, adapted to

engage with the operating-shoulder 8 on the bolt 4 when said lock-barrel is rotated. A guard-plate 15 is provided with a stem 16, which stem is adapted to extend into the outer portion of the key-slot 13 in the lock-barrel 11 and be held therein in any suitable manner, as by the screw 17. The stem of said guard-plate is provided with the grooves 18, extending therethrough, each of which groove is adapted to receive a tumbler 19, 55 which tumblers are headed on their inner ends to hold them from displacement. The outer edge of said guard-plate is notched to form the fingers 20, the outer ends of which fingers overhang at one side.

Forward of the lock-barrel and within the case 1 I support the bracket 21, providing bearings for the square sliding keeper-rods 22, each of which rods bear at its outer end and fixed rigidly thereon one of the keepers 23. Between the sides of the bracket 21 the keeper-rods support coil-springs 24, held between the forward sides of said bracket and a pin 25, extending through a suitable opening in each of said rods, the tendency of said 65 springs being to normally hold the keepers in a forward position. One side of each of the keepers is provided with a notch 26 to receive the sidewise-projecting forward end of one of the fingers 20 of the guard-plate. The 70 forward edge of each keeper is cut away to form an inclined surface 27 for the impingement of the ends of the tumblers. The inner ends of the tumblers are adapted to lie each within its notch in the key, and when said 75 key, and with it the lock-barrel, is rotated the outer ends of the tumblers are brought into engagement with the inclined surface 27 of the keepers, pushing said keepers backward against the action of the coil-springs 24, surrounding the rods 23. The rotation of the lock-barrel moves the fingers 20 of the guard-plate downward into coincidence with the notches 26 in the sides of said keepers. The stud 14 of the lock-barrel engages the operating-shoulder 8 of the bolt 4 and draws said 80 bolt backward into the lock-case. Each of the tumblers is of a suitable length to push backward its coinciding keeper the proper 85 distance to permit the passage of the fingers 90 100

20 of the guard-plate 15 through the notches 26 of the keeper. If the wrong key is inserted into the key-slot of the lock-barrel, one or more of the tumblers will project from 5 said barrel too far or not far enough, depending upon the form of the key, to properly push back one or more of said keepers, and as a result the fingers 20 of the guard-plate 15 will impinge upon the tops of said keepers, and 10 thus prevent the rotation of the lock-barrel.

In changing the lock to adapt it to a different form of key the lock-barrel is removed from the case 1, the guard-plate 15 taken from the barrel, and the tumblers replaced 15 by new tumblers of a maximum length. With the heads of the tumblers resting in their proper notches in the new key the outer ends of said tumblers are cut or filed away until they lie in the same plane and extend out- 20 ward from the lock-barrel a proper distance. The lock-barrel is then replaced and the lock is again ready for use. To withdraw the key, the tumblers must be turned downward, so that their heads will fall out of the way of the 25 shoulders formed by the notches in said key.

This form of lock is particularly adapted for use in safety-deposit vaults and other lock-boxes where it is desirable to hold the key in the lock until the bolt is thrown for- 30 ward—that is to say, to make it impossible to remove the key while the closure that the lock guards is unlocked. The bolt may be retained in its retracted position by a suitable catch if it is desirable to operate the 35 lock in this manner.

It is apparent that various changes might be resorted to in the general form and arrangement of the several parts herein described without departing from the spirit and 40 scope of my invention, wherefore I wish to have it understood that I do not desire to limit myself to the precise details set forth.

I claim as my invention—

1. In a lock, in combination, a lock-barrel; tumblers for said barrel; an individual keeper 45 for each of said tumblers; a guard-plate adapted to engage said keepers; and a bolt.

2. In a lock, in combination, a lock-barrel; tumblers for said barrel; an individual keeper 50 for each of said tumblers; a guard-plate having grooves for receiving said tumblers and adapted to engage said keepers; and a bolt.

3. In a lock, in combination, a lock-barrel slotted longitudinally; tumblers adapted to lie in said slot; keepers for said tumblers 55 adapted to lie in the path of movement of said tumblers; a guard-plate having grooves adapted to receive said tumblers and extending into the slot in the lock-barrel and rotatable with said barrel; and a bolt. 60

4. In a lock, in combination, a lock-barrel slotted longitudinally; tumblers adapted to lie in said slot; keepers yieldingly mounted, adapted to lie in the path of movement of said tumblers and be engaged by said tum- 65 blers; a guard-plate rotatable with said barrel and having fingers adapted to pass be- side said keepers; and a bolt.

5. In a lock, in combination, a lock-barrel slotted longitudinally; tumblers adapted to 70 lie in said slot; keepers for said tumblers, which keepers are yieldingly supported with reference to said lock-barrel and are adapted to lie in the path of movement of said tumblers; a guard-plate rotatable with said bar- 75 rel, said guard-plate having fingers at one side and at its other side being adapted to extend into the slot in said lock-barrel; and a bolt.

IVAN WIDE.
